UNITED STATES PATENT OFFICE.

BENJAMIN FULTON GARDNER, OF CHICAGO, ILLINOIS, ASSIGNOR OF ONE-HALF TO
SEYMORE STEDMAN, OF CHICAGO, ILLINOIS.

ELECTRICAL SIGNALING SYSTEM.

1,233,046.

Specification of Letters Patent. Patented July 10, 1917.

Application filed January 18, 1916. Serial No. 72,737.

To all whom it may concern:

Be it known that I, BENJAMIN FULTON GARDNER, a citizen of the United States, residing at Chicago, in the county of Cook 5 and State of Illinois, have invented new and useful Improvements in Electrical Signaling Systems, of which the following is a specification.

My invention relates to improvements in 10 electrical signaling systems. More particularly the invention is concerned with a means for energizing such systems from a three-wire distribution line having its neutral wire grounded as is common in central- 15 station supply systems. The type of apparatus to be employed is preferably the same as that illustrated and described in my companion application, Serial No. 69,568, filed Dec. 31, 1915, for a means for energizing 20 electrical signaling systems. The present invention is concerned with the operation of an apparatus of the general type of my companion application when used in connection with the three-wire system referred 25 to, it being my object to provide an arrangement by which the signaling circuit may be operated at the predetermined voltage and by no possibility may this voltage be exceeded, either between the two sides of the 30 signaling system itself, or between either side of the same and the ground, and whether the main-line circuit or the signaling circuit be open or closed.

In short it is my object to so arrange the 35 apparatus that although it be energized by direct connection with a relatively high voltage service line, or main-line, the signaling circuit will be in all respects as safe both as to life and fire hazard as though it 40 were energized from a battery or dynamo of the proper low potential.

With this object in view I have provided 45 the arrangement illustrated diagrammatically by the accompanying drawing, in which—

Figure 1 is a diagrammatic view of a preferred form of apparatus embodying the invention; Fig. 2 is a schematic diagram illustrating one modified circuit arrangement, 50 and Fig. 3 is a schematic diagram illustrating a second modified circuit arrangement.

In the drawing, the numeral 1 (Fig. 1) designates the two main-line wires of a three-wire distribution system, and the numeral 2 designates the neutral or third wire 55

of the system, which will, in common practice, be grounded at one end as at 3, and split up into a plurality of distribution lines each paralleling one of the main-line wires, the system being thus divided into two parts 60 with the current-consuming devices, designated 4, designed to approximately balance one another, as is well understood.

To apply my signal-energizing device to this type of circuit, I preferably provide a 65 two-pole electromagnetic switch or relay, designated 5, and arranged to open or close simultaneously the main-line wire 1 and neutral wire 2, through a resistance comprising members 6, 6', arranged in series, 70 the latter being preferably composed of two or more conductors in parallel with one another, as shown in Fig. 1, the purpose being that if one of the members 6' should fail, the other will prevent the circuit from opening 75 at this point.

For energizing the coils of the relay to cause it to thus open and close the circuit through the resistances 6, 6', I provide an independent battery circuit designated 7 80 and having a battery 8 and a suitable control switch or button 9 therein. Since the sole function of the battery circuit is to operate the relay, the battery may obviously be of the smallest commercial size and 85 power, the power demand upon even a single dry cell being so slight that it will, in practice, depreciate more by lapse of time than by use.

Shunted around that end 6' of the resistance which is connected to the neutral wire 2 is the signaling circuit proper, designated 10 and shown as having a bell 11 and telephone hook 12 therein. The signal shunt circuit 10 is designed to be constantly closed, 95 except in so far as it may be opened by the operation of the signaling devices themselves. The potential difference or voltage of the signal shunt will be predetermined by the main-line voltage and the relative resistances of the members 6 and 6'. Thus the main-line may be a 220 volt system, giving 110 volts from each of its sides to the neutral wire. With a current of 1 ampere the resistances 6 and 6' may be adjusted in value 100 so that there will be an 80 volt drop in the resistance 6 and a 30 volt drop in the resistance 6', which latter will then be the impressed E. M. F. for the signal shunt 10.

In operation the relay will normally 110

maintain the main line wire 1 and neutral wire 2 open, so that there will be no possibility of any current flowing through the apparatus, and the signal line will of course be wholly dead, both as between its two sides and between either side and the ground. When the switch 9 of the control circuit is closed, the relay will be actuated to simultaneously close the lines 1 and 2 through the resistance 6, 6'. The drop of potential between the ends of the resistance 6' will thereupon energize the shunt 10 and the signaling devices therein, establishing the predetermined potential difference on the two sides thereof. Since the resistance 6' is connected directly to the neutral or ground wire 2, there will be no potential difference between ground and one side of the signal shunt, while between the other side and ground only the predetermined 30 volt difference will exist. The shunt signal circuit therefor may be wired and protected according to the requirements of its limited voltage only and in the same manner as systems of like voltage energized from battery installations.

While I have shown a double-pole electromagnetic switch for opening both the line wire 1 and neutral wire 2, it will be understood that the neutral wire switch may be dispensed with without interfering with or changing the normal operation of the device, the double-pole switch being preferred however as a measure of additional security.

In Fig. 2 I have illustrated one such modification, in which the main-line wires 21 and neutral 22 are arranged in the same fashion as in Fig. 1. The resistances 26, 26' are connected between one of the main-line wires and the neutral wire as shown, and the signal circuit 30 is shunted around the resistance 26'. I have omitted the battery circuit in this figure, showing only a simple switch 25 for opening and closing the main-line wire 21, the neutral wire being kept constantly connected with the resistance 26', thus grounding the latter.

In Fig. 3 I have illustrated a further modification, similar in all respects to Fig. 2 save that the switch, here designated 35, is located between the resistances 26 and 26'.

It is believed that the manner of operation of the circuits shown in Figs. 2 and 3 will be clear from the description of the preferred construction. It will be understood that in both Figs. 1 and 2 the switches 25, 35, should preferably be electromagnetically operated from independent circuits, as in Fig. 1.

The mechanical construction and arrange-

ment of the parts illustrated by the dia-grammatic drawing accompanying this specification may be the same as that shown and described in my co-pending application heretofore referred to.

65

It should be understood that the structure described by this specification is illustrative only and for the purpose of making my invention more clear, and that I do not regard the invention as limited to any of the particularities of construction chosen for purposes of illustration, except in so far as I have included such limitations within the terms of the following claims.

70

What I claim is:

1. The combination with a three wire distribution system having its neutral wire grounded, of a resistance member interposed between the neutral wire and one of the main-line wires of such system, a signal shunt-circuit having one end connected to said neutral wire and its other end connected to said resistance intermediate the length of the latter, signaling devices in the said signaling circuit, and means for opening and closing the main line wire ahead of the point of connection of said signal shunt with the said resistance.

2. The combination with a three wire distribution system having its neutral wire grounded, of a resistance member interposed between the neutral wire and one of the main-line wires of such system, a signal shunt-circuit having one end connected to said neutral wire and its other end connected to said resistance intermediate the length of the latter, signaling devices in the said signaling circuit, a relay for opening and closing the main-line wire ahead of the point of connection of said signal shunt with the said resistance, and an independent circuit for energizing the said relay.

3. The combination with a three wire distribution system having its neutral wire grounded, of a resistance member interposed between the neutral wire and one of the main-line wires of such system, a signal-shunt circuit having one end connected to said neutral wire and its other end connected to said resistance intermediate the length of the latter, signaling devices in said signaling circuit, a double-pole relay for opening and closing said main-line and neutral wires, and an independent circuit for energizing said relay.

BENJAMIN FULTON GARDNER.
